Term of patent 3½ years

(Cl. D14—3)

FIGURE 1 is a front perspective view of a frame for a child's cart showing my new design.

FIGURE 2 is a side elevational view thereof.

The rear is substantially plain aside from the panel pattern which is the same on the rear and side not shown as on the side shown.

This application is a division of my earlier application, Serial No. D. 53,107, filed October 23, 1958, now abandoned.

I claim:

The ornamental design for a frame for a child's cart, as shown and described.
